UNITED STATES PATENT OFFICE

ALBERT BIRCH, OF BELMONT, MASSACHUSETTS

CLOTH-HANDLING MACHINE

Application filed November 30, 1927. Serial No. 236,744.

This invention relates to a cloth-handling machine such as is used to open and spread out flat a web of cloth as it is taken from a dye vat or other similar receptacle or otherwise being operated upon and to guide the opened web in its passage to some machine such as a drying machine or cloth-finishing machine, etc. One form of cloth opener and guide which is now commonly used comprises 10 a pair of conical rollers over which the cloth to be opened is drawn and which are journalled on a pivoted support with their axes having an angular relation to each other and with the smaller end of the rollers at the 15 apex of the angle. These rollers are normally freely rotatable and are rotated by the cloth as the latter is drawn over them, said rollers operating to open the web of cloth and deliver it in a flat condition. So long as the web is 20 centrally located on the rolls the pivoted support will maintain its central or neutral position but if during the travel of the web over the rolls the latter moves laterally so that one roll supports a greater portion of the 25 web than the other then the pivoted support will be deflected downwardly at one end.

In prior devices means have been provided whereby when one end of the support is thus deflected downwardly the roller on said 30 end will be locked against rotation and the combined result of the increased friction on the stationary roller and the rotative movement of the opposite roller the fabric will be moved laterally to central position again at 35 which time the support will again resume its central or neutral position thus unlocking the locked roller.

The present invention has for one of its 40 objects to improve devices of this type by providing means whereby as one or the other of the pivoted supports is deflected the corresponding roller will be frictionally retarded rather than locked against rotation. This 45 results in producing a more sensitive guide which holds the fabric more accurately to its central position.

Another object of the invention is to provide 50 an improved central bearing for the meeting ends of the rollers and to provide

other features of improvement all as will be more fully hereinafter set forth.

In the drawings wherein I have illustrated a selected embodiment of my invention, Fig. 1 is a plan view of a cloth opener and 55 guide made in accordance with my invention; Fig. 2 is a side elevation of Fig. 1;

Fig. 3 is an enlarged view partly in section showing the bearing at the large ends of the 60 rollers;

Fig. 4 is a sectional view of the central bearing;

Fig. 5 is a side view of the device on an enlarged scale;

Fig. 6 is a section on the line 6—6, Fig. 3. 65

The guiding rollers over which the cloth is drawn are indicated at 1 and 2. These rollers may be corrugated, serrated, grooved, threaded or otherwise formed and they may be straight or conical as desired. In the illustrated embodiment of the invention these 70 rollers are conical rollers and are shown as having corrugated surface. Said rollers are journalled on a support 3 which in turn is pivotally mounted upon a suitable frame 4. The rollers have an angular relation to each 75 other with the smaller ends of the rollers at the apex of the angle as usual in devices of this sort.

The smaller ends of the conical rollers are 80 journalled in a central bearing 5 and the larger ends of the rollers are journalled in bearings 6.

The support 3 is provided with the trunnions 7 that are supported in bearings 8 carried by the frame 4 whereby said support is adapted to swing or turn about the trunnions. 85

One feature of the present invention relates to a novel means for frictionally retarding each roller whenever the cloth tends to move laterally from its central position. For this purpose means are provided for applying a frictional braking pressure to one or the other of the rollers as the support 3 tilts depending on the extent and direction of the tilting movement. Any appropriate form of brake may be employed without departing from the invention. In the illustrated embodiment I have shown a brake in the form 90 of an external brake. 95

The large end of each roller is provided with a cylindrical braking surface 9 with which a friction brake 10 co-operates. This brake is pivoted on a pin 11 extending from the bearing or bracket 6 and it is provided with an arm 12 that is formed with a ball end 13 that is received in a socket 14 provided at the upper end of a stud 15, the latter being secured rigidly in the frame 4.

10 The brake is so constructed that when the support 3 is in its neutral central position the brake will be disengaged or separated from the braking surface 9 as shown in Fig. 5. If, however, the support 3 tilts downwardly at either end, as shown by the dotted line, Fig. 5, such downward movement will cause a swinging movement of the brake because of the fact that the end 13 is held in the stationary socket 14 and the brake will be applied to the surface 9. The degree of braking pressure which results will depend upon the extent of tilting movement of the support 3.

If during the operation of the machine the cloth tends to move laterally from its central position the support 3 will begin to tilt downwardly at one end and as this movement commences the brake will be applied thus retarding the rotation of the roll. If the retardation is sufficient to correct the tendency of the cloth to move laterally then there will be no further tilting movement of the support and as the cloth resumes its normal central position the support will return to its balanced condition and the braking pressure will be relieved. On the other hand, if a slight braking pressure resulting from the initial tipping movement does not sufficiently retard the roller to cause the cloth to be brought back to its central position and the support continues to tilt the result will be that the braking pressure will be applied to a greater extent thus further retarding the roller. This retardation of the roller will continue until it is sufficient to cause the cloth to be brought back to its central position.

With my invention the roller is not necessarily locked against rotation but its rotation is merely retarded and this makes a much more sensitive apparatus.

Another feature of the invention relates to a construction wherein the central bearing 5 is protected from contact with the cloth. This bearing 5 comprises a post having a head 16 at its upper end provided with two sockets 17 in which the ends 18 of the shafts of the rollers 1 and 2 are received.

The small ends of the rollers 1 and 2 are recessed as shown at 19 and the ends 21 of the head 16 are received in the recesses. These recesses form flanges 20 which overlie the head and protect the same from contact with the cloth.

I have also provided the bearing members 6 in which the outer ends of the rollers 1 are

journalled with ball or roller bearings 22 in which the ends 23 of the roller shafts are received. These ball or roller bearings are received in recesses 24 formed in the bearing member 6 and are retained in place by means of suitable removable caps 25.

If desired, the ball or roller bearings 22 may have a loose fit in the recess 24 so as to allow for slight deflections in the shaft 23 without causing any binding of the parts. 75

I claim:

1. In a device of the class described, the combination with a main frame, of a rigid support pivoted centrally on the main frame, two guiding rollers over which the cloth is drawn and which are journalled in bearings stationarily mounted on said rigid support, a braking device for each roller pivoted to the supporting frame and an actuating arm for each brake pivoted to the main frame. 85

2. In a device of the class described, the combination with a supporting frame, of a rigid support pivoted centrally on the frame, two guiding rollers journalled in the support and over which the cloth is drawn, each roller having a peripheral frictional surface, a brake member for each roll pivoted to the supporting frame, and an arm extending from each brake member and having a pivotal connection with the main frame, whereby as the supporting frame tilts the brake will be applied to one or the other of the rollers. 90

3. In a device of the class described, the combination with a supporting frame, of a rigid support pivoted centrally on the frame, two guiding rollers journalled in the support and over which the cloth is drawn, each roller having a peripheral frictional surface, a brake member for each roll pivoted to the supporting frame, and an arm extending from each brake member and having a sliding connection with the main frame, whereby as the supporting frame tilts the brake will be applied to one or the other of the rollers. 100

4. In a device of the class described, the combination with a supporting frame, of a rigid support pivoted centrally on the frame, two guiding rollers journalled in the support and over which the cloth is drawn, each roller having a peripheral frictional surface, a brake member for each roll pivoted to the supporting frame, and an arm extending from each brake member and having a ball-shaped end and a socket rigid with the main frame and in which the ball is slidingly and pivotally received. 115

In testimony whereof, I have signed my name to this specification.

ALBERT BIRCH. 125
